[57] **CLAIM**

The ornamental design for an armchair, as shown and described.

DESCRIPTION

FIG. 1 is a front perspective view of an armchair showing my new design;

FIG. 2 is a front elevational view;

FIG. 3 is a side elevational view, the other side being a mirror image thereof; and

FIG. 4 is a rear elevational view thereof, the bottom being plain and unornamented.

The fabric pattern schematically depicted in the several views is continuous throughout.

FIG. 1

FIG. 2

FIG. 3

FIG. 4
